(57) CLAIM

The ornamental design for a merchandiser, as shown and described.

DESCRIPTION

FIG. 1 is a perspective view of a merchandiser showing our new design;

FIG. 2 is a left side view thereof;

FIG. 3 is a front view thereof;

FIG. 4 is a right side view thereof; and,

FIG. 5 is a top view thereof.

The broken line showings in FIGS. 1-5 are for the purpose of illustrating the environment of the design and form no part of the claimed design.

1 Claim, 5 Drawing Sheets
